US00D826948S

(12) **United States Design Patent** (10) **Patent No.:** **US D826,948 S**
(45) **Date of Patent:** **** Aug. 28, 2018**

(54) **SUPPORT FOR ELECTRONIC DEVICE**

(71) Applicant: **Shenzhen Rubao Technology CO. LTD**, Shenzhen (CN)

(72) Inventor: **Bo Xiao**, Ji'an (CN)

(73) Assignee: **Shenzhen Rubao Technology CO. LTD**, Shenzhen (CN)

(**) Term: **15 Years**

(21) Appl. No.: **29/616,195**

(22) Filed: **Sep. 4, 2017**

(51) LOC (11) Cl. **08-07**

(52) U.S. Cl.

USPC **D14/447**

(58) **Field of Classification Search**

(57) **CLAIM**

The ornamental design for a support for electronic device, as shown and described.

DESCRIPTION

FIG. 1 is a perspective view of a support for electronic device showing the new design;

FIG. 2 is a front view of the support for electronic device;

FIG. 3 is a rear view of the support for electronic device;

FIG. 4 is a left view of the support for electronic device;

FIG. 5 is a right view of the support for electronic device;

FIG. 6 is a top side view of the support for electronic device; and,

FIG. 7 is a bottom side view of the support for electronic device.
